UNITED STATES PATENT OFFICE.

MAX J. SPERLING, OF CHICAGO, ILLINOIS.

SHOE-CLEANING DEVICE.

Application filed August 8, 1923. Serial No. 656,402.

To all whom it may concern:

Be it known that I, MAX J. SPERLING, a citizen of the United States, and a resident of the city of Chicago, in the county of Cook and State of Illinois, have invented certain new and useful Improvements in a Shoe-Cleaning Device; and I do hereby declare that the following is a full, clear, and exact description of the same, reference being had 10 to the accompanying drawings, and to the numerals of reference marked thereon, which form a part of this specification.

This invention relates more particularly to an improved shoe cleaning stand adapted 15 to be rigidly secured to a floor in a position to permit a shoe when on a person's foot to be inserted in a brush containing casing and moved back and forth therein whereby the brushes act to remove dust and dirt from the 20 shoe to clean the same.

It is an object of this invention to provide a shoe cleaning device having adjustably mounted side brushes permitting shoes of different sizes to be cleaned in the device.

It is also an object of the invention to provide a shoe cleaner device wherein all of the 25 brushes may be readily removed for cleaning or replacement.

Another object of the invention is the construction of a shoe cleaning stand having removable brushes therein certain of which are resiliently held in position so that shoes of different sizes may be cleaned.

It is an important object of this invention 35 to provide a shoe cleaning device of improved construction adaptable for cleaning shoes of different sizes and so made that the brush members may be readily assembled and removed for cleaning or replacement 40 when necessary.

Other and further important objects of this invention will be apparent from the disclosures in the specification and the accompanying drawings.

The invention (in a preferred form) is 45 illustrated in the drawings and hereinafter more fully described.

On the drawings:

Figure 1 is a top plan view of a shoe 50 cleaning device embodying the principles of this invention.

Figure 2 is an end elevation of the entrance end of the device.

Figure 3 is a side elevation of the device.

Figure 4 is an enlarged horizontal section 55 taken on line 4-4 of Figure 2.

Figure 5 is a vertical longitudinal section taken on line 5-5 of Figure 1.

Figure 6 is a transverse section taken on line 6-6 of Figure 3.

Figure 7 is a fragmentary detail view taken on line 7-7 of Figure 6 with parts omitted.

Figure 8 is a detail view taken on line 8-8 of Figure 6 with the casing parts omitted.

As shown on the drawings:

The reference numeral 1 indicates a base frame curved at one end and straight at the other end. Rigidly secured on the base 70 frame 1 are casing side walls 2 which are integrally connected by a curved end wall 3. The base frame is supported on flanged or double angle legs 4 which are adapted to be rigidly secured to the floor to hold the device in a rigid position for use. Positioned within the shoe cleaning casing formed by the walls 2 and 3 is a base or bottom brush comprising a back board 5 having a plurality of sets of upwardly directed brush bristles 6 supported thereon. The base brush rests on the base frame 1 against the curved back 7 of an end or tip brush provided with sets of bristles 8 of different lengths positioned to afford a shoe tip or toe receiving 85 recess 9.

The inner side of each casing wall 2 is provided with a long recess 10. Rigidly secured by means of staples 11 to the inner side of each side wall 2 are the outer ends of 90 a plurality of coiled springs 12. The inner ends of the coiled springs 12 are attached to a slidable metal plate 13 by means of retaining bars 14 (Figure 8). Positioned within the casing against each spring impelled plate 95 13 is a side brush back 14^a provided with sets of bristles 15. The side brush bristles 15 are of different lengths to afford an irregular brushing surface adapted to engage the sides and the soles of shoes. Removably 100 secured by means of screws 16 to the upper edge of each casing side wall 2 is a casing

top board 17, the inner edge of which has an integral rib or stop flange 18 formed thereon against which the side brush back 14 is adapted to be resiliently held by the action of the springs 12.

The casing also comprises an end top plate 19 which is removably secured to the top edge of the curved casing end wall 3 and abuts against the ends of the top boards 17.

10 Integrally formed on the top plate 19 is an arched top brush back 20 and depending lugs 20^a integral therewith having sets of brush bristles 21 secured on the inner surface thereof. The top brush bristles 21 are 15 of different lengths and are arranged to afford a recess or pocket 22 which registers with the tip recess 9 formed by the bristles 8. The registering recesses 9 and 22 are shaped to receive the tip and fore part of a 20 shoe to be cleaned by the bristles 8 and 21. The bristles 15 of the side brushes serve to clean the sides of the shoe, while the bristles 6 of the bottom brush act on the sole of the shoe to clean the same.

25 To hold the various brushes in place within the casing a U-shaped end plate 23 is removably secured to the open end of the casing by means of headed nails or screws 24. The heads of the nails 24 at the sides of the 30 casing are adapted to be engaged through the enlarged portions of inverted key slots 25 (Figure 2), while the nail 24 at the lower central portion of the casing is projected through a slot 26. The end plate 23 is thus 35 adapted to be readily placed in position on the end of the casing or removed therefrom.

The operation is very simple. In order to 40 clean a shoe worn by a person it is only necessary to push the shoe into the open end of the brush casing and then move the shoe back and forth so that the bristles of the various brushes will act to clean the shoe at the bottom, sides, vamp and tip. The opening in the top of the casing between the top 45 plates 17 permits the leg of a person to project into the casing and to be moved back and forth to bring the shoe into contact with the various cleaning brushes.

Normally the coiled springs 12 serve to 50 resiliently hold the side brushes projected toward one another with the brush backs engaged against the stop flanges 18 (Figure 2). The side brushes being movably mounted in place permit shoes of different width to be 55 cleaned. In case the brushes need cleaning the end plate 23 is slightly lifted and then removed from engagement with the nails 24. The side brushes and the bottom brush may then be pulled out of the open end of the 60 casing. When the side brushes are removed the springs 12 act to move the metal plates 13 against the stop flanges 18. The brushes 7 and 20 may be removed for cleaning by removing the top plate 19 on which the top brush 20 is formed.

While bristle brushes have been illustrated and described for use in the shoe cleaning casing, it is to be understood that some or all of the bristle brushes may be replaced by felt brushes if desired.

70

I am aware that numerous details of construction may be varied through a wide range without departing from the principles of this invention, and I therefore do not purpose limiting the patent granted otherwise 75 than necessitated by the prior art.

I claim as my invention:

1. A shoe cleaning device comprising a casing having an opening in one end and in the top, means on said casing for supporting 80 the same, a tip brush and a top brush in said casing, a bottom brush and side brushes also mounted in the casing, and an end plate removably engaged on the open end of the casing for holding the bottom brush and the side brushes in place within the casing against longitudinal removal.

2. A shoe cleaning device comprising a casing open at the top and at one end, a tip brush in the closed end of the casing, a top plate closing the top of the closed end of the casing, a brush formed on said top plate and projecting into the casing, a bottom brush resting on the floor of the casing, side brushes in said casing resting on the bottom brush, spaced top boards secured on the top of the casing for holding the side brushes in place, and an end plate having an opening therein removably secured to the open end of the casing for holding the bottom brush and the side brushes in place against longitudinal removal.

90

3. A shoe cleaning device comprising a casing having openings therein, a tip brush in one end of the casing, a top brush on the casing, a bottom brush disposed on the floor of the casing, side brushes in the casing, spaced top plates secured on the casing, stop flanges formed thereon, and resilient means 105 between said side brushes and the side walls of the casing adapted to resiliently hold the side brushes in engagement with said stop flanges.

95

4. A shoe cleaning device comprising a 110 casing having openings therein, a tip brush in said casing, a top brush projecting into the casing, a bottom brush seated on the floor of the casing, side brushes in the casing, spaced top plates secured on the top of the casing to partially close the same, stop flanges formed on said top plates, plates 115 slidably disposed between the side brushes and the side walls of the casing, and springs attached to said slidable plates and to the casing side walls to cause the slidable plates to act on the side brushes and hold the same against the stop flanges.

120

5. A shoe cleaning device comprising a 125 casing, and a plurality of brushes lining the casing with the brush bristles projecting in

130

different directions and of different lengths to afford a shoe receiving recess substantially of the shape of, and enveloping, the entire tip of the shoe to be cleaned.

- 5 6. A shoe cleaning device comprising a casing, shoe cleaning brushes movably mounted therein adapted to be moved when a shoe is inserted in the casing to be cleaned, spaced top plates secured to the top edges of 10 the casing and having stop members thereon,

and means in the casing for resiliently moving the brushes toward one another and into resilient contact with the stop members whereby said brushes will be forced inwardly and resiliently engage a shoe placed 15 therebetween.

In testimony whereof I have hereunto subscribed my name.

MAX J. SPERLING.
